UNITED STATES PATENT OFFICE.

HOWARD M. CROCKER, OF MANKATO, MINNESOTA.

SILO-DOOR LATCH.

1,330,847.

Specification of Letters Patent. Patented Feb. 17, 1920.

Application filed February 26, 1918. Serial No. 219,282.

To all whom it may concern:

Be it known that I, HOWARD M. CROCKER, a citizen of the United States, residing at Mankato, in the county of Blue Earth and 5 State of Minnesota, have invented certain new and useful Improvements in Silo-Door Latches, of which the following is a specification.

This invention relates to silo door fasteners and has for its object the production of a 10 simple and efficient silo door fastener which may be very quickly and efficiently operated for the purpose of clamping the door in a locked or closed position and which may be 15 also quickly and efficiently released for the purpose of permitting the door to be moved to an open position.

Another object of this invention is the 20 production of a simple and efficient lock means carried by the door and door frame, whereby the door will be firmly clamped and tightly held upon the door frame in such a manner as to tightly seal the door against the door frame.

25 With these and other objects in view this invention consists of certain novel constructions, combinations and arrangements of parts as will be hereinafter fully described and claimed.

30 In the drawings:—

Figure 1 is a front elevation of a portion of the silo door frame, the doors being shown in a set position or locked position,

Fig. 2 is a transverse sectional view 35 through the door frame and door,

Fig. 3 is a side elevation of a portion of the door frame, showing especially the locking and clamping means for the door,

Fig. 4 is a side elevation of one of the 40 locked wedge plates,

Fig. 5 is a section taken on line 5—5 of Fig. 4,

Fig. 6 is a detail perspective of the locking 45 lever used in connection with the door, the locking lever being shown connected to the door, the door being shown partly in section,

Fig. 7 is a detail perspective of a modified 50 form of one of the locked wedge plates, showing the locked wedge being formed from a blank sheet of material.

By referring to the drawings, it will be seen that 1 designates the door frame of the silo which may be made of any suitable or 55 desired construction without departing from the present invention especially in view of

the fact that this invention resides more particularly in the locked or clamping portion of the door. A door 2 is mounted within the frame 1 and is adapted to close the 60 door way formed in the frame 1 and this door 2 is provided with a plurality of longitudinally extending spaced reinforcing ribs 3 as shown in Fig. 1 of the drawings.

A locking lever 4 is pivotally secured to 65 the longitudinally extending reinforcing rib 3 by means of suitable bolts 5 extending through the inner end 6 of the locking lever 4 as shown in Fig. 6 of the drawings. The inner ends 6 of the locking lever 4 are provided with laterally extending enlarged portions 7 upon the sides, these portions 7 being provided with abrupt shoulders 8 upon the inner ends thereof as shown in Figs. 2 and 6 of the drawings. These shoulders 8 75 are preferably curved upon the inner faces thereof, as indicated clearly in Fig. 3 of the drawings, for the purpose of facilitating the moving of the shoulder portion 8 over the wedged plates 9 which are secured to the 80 sides of the frame 1.

As shown in Fig. 2, suitable wedge plates 9 are secured to the sides of the frame 1 and each of these wedge plates 9 comprises a flat body portion having a plurality of securing apertures 10 formed therein, through 85 which securing apertures 10 extend suitable pins 11 for the purpose of facilitating the securing of the wedge plates 9 through the frame 1. Each of the wedge plates 9 is pro- 90

vided with an inclined outer face 12 as shown in Fig. 4, each plate 9 being thickened upon the outer edge thereof as indicated at 13 in Fig. 5 for the purpose of constituting a broad or reinforcing bearing face upon 95 which the overhanging shoulder portions 8 of the lever 4 are adapted to work for the purpose of firmly clamping the door 2 in engagement with the frame 1. The forward edge 12 of each of the wedge plates 9 tapers 100 inwardly toward the upper end of the plate for the purpose of facilitating the tightening of the lever 4 upon the upper end of the plate 9 as the lever is swung downwardly.

In view of the fact that the locking plates 9 105 are provided with inclined faces 12, it will be seen that as the lever 4 is swung downwardly as shown in Fig. 1, the door 2 will be drawn in tight engagement and wedged in engagement with the frame 1, due to the 110 fact that the overhanging portions 7 firmly bear against the inclined faces 12 of the

locking or bracing plate 9 and firmly lock the door in a closed or set position.

As shown in Fig. 7 these wedging plates 9 may be formed of sheet metal and in the modified form which is shown in Fig. 7 a sheet metal body portion 14 is employed from which sheet metal body portion 14 are extended in a lateral direction, a plurality of supporting feet 15, the feet 15 being adapted to be secured to the outer face of the frame of the silo. The sheet metal body portion 14 is formed so as to provide an inclined outer face 16, tapering toward the upper end of the body, and this face 16 is formed by means of the laterally extending flange 17 bent from the body 14 as shown in Fig. 7, this flange 17 will constitute a reinforcing means against which the overhanging portion 7 of the locking lever 4 is adapted to rest for the purpose of firmly clamping the door 2 in a set or locked position upon the door frame 1.

From the foregoing description, it will be seen that a very simple and efficient means has been produced in the nature of a silo door lock, whereby the locking lever 4 may be easily and conveniently swung to a locked or unlocked position, and while the locking lever 4 is swung to a locked position, the same will constitute an efficient ladder for the silo, these locking levers 4 being held by gravity in engagement with the wedging plates 9.

It should be of course understood that certain obvious detail mechanical changes may be made in the present device without departing from the spirit of the invention, so long as these changes fall within the scope of the appended claims.

As shown in Figs. 3 and 4, the inclined faces 12 are provided with an enlarged portion 12' at the lower ends thereof for the purpose of constituting an abutment or positive stop for limiting the downward swinging movement of the locking lever 4 should an extraordinarily heavy weight be placed upon the locking lever. It of course should be understood that this locking lever 4 is ordinarily used as a ladder, notwithstanding the fact that the same is also used for the purpose of locking the door in a closed position and the weight of a man climbing upon the locking lever 4 which constitute the ladder might force the lock-

ing lever downwardly to such a position as to cause the same to overrun the inclined face or faces of the wedging plates 9. Should the locking lever 4 move downwardly to the lower end of the wedging plates 9, the enlarged portion 12' will constitute a positive abutment against which the lever will rest and thereby hold the same against further movement or against being accidentally detached from engagement with the wedging plates 9. 65

What is claimed is:

1. In a door, the combination with a door frame, a door fitting upon said frame, a locking lever provided with inwardly extending end portions and a transversely extending connecting portion constituting a step, said inwardly extending portions being pivotally secured at their inner extremities to said door, said inwardly extending end portions also provided with an enlarged laterally extending thickened lug upon the outer sides thereof intermediate the ends of the end portions, wedging plates secured to said frame, and said thickened laterally extending lug being adapted to ride upon the inclined face of said wedging plate whereby pressure upon the step and locking lever will draw said door tightly in engagement with said frame and cause said wedging plate to be firmly clamped in engagement with the supporting frame. 70

2. In a silo door mechanism and locking means therefor, the combination with a door frame having an opening formed therein, a door adapted to close said opening in said frame, of a locking lever provided with inwardly extending end portions being pivotally secured at their inner extremities to said door, said inwardly extending end portions carrying laterally extending portions, wedging plates secured to said frame and provided with inwardly inclined outer faces adapted to receive the laterally extending portions whereby said door will be firmly drawn into a closed position within said opening in said frame, and whereby pressure exerted upon said locking lever will also firmly clamp the wedging plates in engagement with said frame. 100 105

In testimony whereof I affix my signature.

HOWARD M. CROCKER.
